(57) **CLAIM**

I claim the ornamental design for a wave modular tableware tile, as shown and described.

DESCRIPTION

FIG. 1 is a top perspective view of the wave modular tableware tile embodying the present invention;
FIG. 2 is a bottom perspective view thereof;
FIG. 3 is a top view thereof;
FIG. 4 is a bottom view thereof;
FIG. 5 is a side view thereof;
FIG. 6 is another side view thereof;
FIG. 7 is a cross-sectional view thereof taken along line 7-7 of FIG. 3; and,
FIG. 8 is perspective view thereof shown in an environment of use with the broken lines forming no part of the claim.

1 Claim, 4 Drawing Sheets
